UNITED STATES PATENT OFFICE.

WADE H. EMRICK, OF WINDY, WEST VIRGINIA.

EXPLOSIVE-ENGINE.

1,273,164.

Specification of Letters Patent.

Patented July 23, 1918.

Application filed January 11, 1913, Serial No. 741,559. Renewed December 22, 1917. Serial No. 208,529.

To all whom it may concern:

Be it known that I, WADE H. EMRICK, a citizen of the United States, residing at Windy, in the county of Wirt, State of West Virginia, have invented certain new and useful Improvements in Explosive-Engines; and I do hereby declare the following to be a full, clear, and exact description of the invention, such as will enable others skilled in the art to which it appertains to make and use the same.

This invention relates to improvements in explosive engines.

The principal object of the invention is to provide an explosive engine of that type in which explosions alternately occur at either end of the piston upon every two successive revolutions.

Another object of the invention is to provide a novel timing mechanism for the sparking means whereby the explosive mixture in the opposite ends of the cylinder will be alternately fired.

Another object of the invention is to provide a novel means for cutting out the explosive mixture from either end of the cylinder whenever it is desired to employ the engine for a light load.

A further object of the invention is to provide an engine of the character described which is extremely simple in construction, it being composed of a minimum number of parts, and is therefore cheap to manufacture.

With these and other objects in view, the invention consists in the construction and novel combination of parts hereinafter fully described, illustrated in the accompanying drawings and pointed out in the claim hereinafter appended; it being understood that various changes in the form, proportion, size and minor details of construction within the scope of the claim may be resorted to without departing from the spirit or sacrificing any of the advantages of the invention.

In the drawings:

Figure 1 is a top plan view of an engine constructed in accordance with my invention,

Fig. 2 is an elevation showing one side thereof,

Fig. 3 is an elevation showing the other side of the same,

Fig. 4 is an end view,

Fig. 5 is a longitudinal sectional view taken on the line 5—5 of Fig. 1,

Fig. 6 is a transverse sectional view taken on the line 6—6 of Fig. 1,

Fig. 7 is a horizontal sectional view 60 through the cylinder,

Fig. 8 is a bottom plan view of the cylinder and of the engine, and

Fig. 9 is a detail sectional view taken on the line 9—9 of Fig. 1.

Like reference numerals designate corresponding parts in all the figures of the drawings.

Referring to the drawings, my invention comprises a base 5, and this base includes a 70 cross head guide 6 and a crank case 7. Suitably mounted upon the base 5 in alinement with the cross head guide 6 is a horizontally disposed cylinder 8 in which is slidably mounted a piston 9. A piston rod 10 is connected to the piston 9 and extends through a suitable boxing 12 into the guide 6, and the end of this rod is connected to a suitable cross head 11 which in turn is connected to a pitman 12 that is connected to 75 a crank 13 of a crank shaft 14, said shaft being suitably supported upon the base 5 and in the crank case 7. Fly-wheels 15—15 are suitably mounted upon the crank shaft 14.

Secured to the opposite ends of the cylinder 8 and offset from one side thereof are valve chambers 16—16 which respectively communicate with the ends of the cylinder 8 through exhaust ports 17. Each chamber 90 includes a valve seat 18 which is normally closed by a valve 19 mounted upon a vertical stem 20, the lower end thereof projecting below the chamber 16 and having a nut 21 fixed thereon. A coil spring 22 is disposed around each stem 20 between the chamber 16 and the nut 21 for yieldably holding the valve 19 upon its seat 18. An exhaust pipe 23 has its ends connected to the valve chamber 16 at points below the 95 valve seat 18, and this pipe is centrally connected to a main exhaust pipe 24.

Carried by the base 5 on the side of the cylinder opposite the valve chambers 16 are spaced bearings 25—25, and journaled in 105 these bearings is a cam shaft 26 which is operatively connected to the crank shaft 14 by means of suitable gearing 27. Depending from the cylinder 8 and in alinement with each exhaust port 17 is a pair of spaced ears 110

28—28, and fulcrumed intermediate its ends, as at 29, between each pair of ears is a rock lever 30. These levers are disposed transversely of the cylinder 8, and are alternately actuated by oppositely disposed cams 31—31 which are fixed on the cam shaft 26. The ends of the levers 30 opposite the cams 31 are disposed under the valve stems 20, and are adapted when actuated to lift said valves 10 to permit of the exhaust from the cylinder passing out through the ports 17 to the exhaust pipe 24, as will be hereinafter more fully explained.

Formed in the wall of the cylinder 8 adjacent each end thereof are inlet ports 32—32, and these ports connect with a main intake pipe 33 through the medium of branch pipes 34—34. Located in each branch pipe 34 is a check valve 35 of any suitable construction, and located in the main intake pipe 33 is a check valve 36 of any suitable construction. The main intake pipe 33 is connected to one end of a pump 37 which is supported upon the base 5 and includes the usual piston 38 and piston rod 39, the latter being connected to a pitman 40 which is operated by an eccentric 41 mounted on the crank shaft 14. The intake end of the pump 37 is connected with a pipe 42 which leads from any suitable source of gas or gasoline.

Formed in each end 43 of the cylinder 8 is an opening 44, and secured to the outer face of each end 43 around the respective opening 44 is a plate 45, and in this plate is journaled a rock shaft 46 which carries a contact finger 47 which engages with and disengages from a fixed contact 48. A wire 49 is connected to the finger 47 and a wire 50 is connected to the finger 48, these wires being suitably connected to any source of electrical energy and a spark coil (not shown). This finger is yieldably held out of engagement with the contact point 48 by means of a spring 51, and extending from the finger is a projection 52. Fulcrumed intermediate their ends, as at 53, upon a respective end 43 of the cylinder 8 are trip levers 54, one end of each lever engaging a respective projection 52 and the other end being engaged by a respective cam 55 which is mounted upon the cam shaft 26, said cams 55 being alternately disposed so as to actuate the trip levers 54 alternately. 55 When each trip lever 54 is actuated, the projection 52 is elevated, and as a result, the contact finger 47 will engage the contact point 48. As soon as the cam 55 becomes disengaged from the lever, the spring 51 swings the contact finger 47 away from the contact point 48, and thereby creates a spark for exploding the mixture within that end of the cylinder.

In order to retain either of the valves 19 open so as to secure explosions in one end

of the cylinder only, there is provided a T-shaped lever 56, the leg 57 thereof being fulcrumed intermediate its ends, as at 58, to the cylinder 8. The head includes oppositely extending arms 59—59, and these arms are adapted to engage either of the rock levers 30, as will be hereinafter explained. In order to lock the lever 30 in any adjusted position so as to retain a respective rock lever 30 in its inoperative position, the upper end 75 of the lever engages over a plate 60 which is carried by the cylinder 8. This plate is formed with three spaced openings 61 and a pin 62 carried by the lever is adapted to engage in any one of the openings 61. 80

In the operation of this engine, assuming the lever 56 to be in its neutral position and consequently out of engagement with either rock lever 30, the rotation of the crank shaft 14 will slide the bottom 9 toward one end of the cylinder, and at the same time actuate the pump 37 to draw in a quantity of explosive mixture through the pipe 42. This pump will then force this mixture through the pipe 37 to the main intake pipe 90 33 and the piston 9 will by suction open one of the valves 35 and the valve 36, thereby drawing the mixture into that end of the cylinder 8. While the piston is returning to compress this charge, a second charge is being drawn into the other end of the cylinder. When the piston has reached its limit of movement, the cam 55 at that end of the cam shaft 26 will actuate the contact finger 47 to close the spark circuit, and as a result, 100 explode the mixture in that end of the cylinder. Immediately following this explosion, the respective cam 31 will actuate the respective rock lever 30, and thereby unseat the valve 19 to permit of the exhaust gases 105 passing out through the exhaust port 17 through the pipe 23 to the main exhaust pipe 24. This operation is of course repeated at the other end of the cylinder.

During this operation a predetermined quantity of air is admitted to the pipes 34 through openings 34', said openings being controlled respectively by needle valve 35.

When it is desired to explode the mixture in one end of the cylinder, only the lever 56 is rocked upon its fulcrum 58 and the pin 62 is engaged within one of the outer openings 61 of the plate 60. This lever will thus be held in its adjusted position, and as a result, the rock lever 30 will be depressed downwardly and consequently out of engagement with its respective cam 31. As a result, the valve 19 will be retained in its raised position and consequently when the piston 9 moves from that end of the cylinder, no suction will take place sufficient to unseat the respective valve 35 and the valve 36. As a result, no mixture will be drawn into this end of the cylinder. It is obvious that in this operation a surplus of fuel would be 110 115 120 125 130

supplied, but this excess fuel supply may be compensated for by any of a number of devices well known in the art, no specific device being shown.

5 What is claimed is:

In an explosive engine, the combination with a cylinder having inlet and exhaust ports respectively formed in either end thereof, of a crank shaft, a piston slidable 10 in the cylinder and operatively connected to said shaft, spring actuated valves including valve stems normally closing the exhaust ports, rock levers each fulcrumed on the cylinder and having one end engaged with a 15 respective valve stem, means actuated by the crank shaft for alternately actuating said levers to unseat the valves, means engage-

able with said levers for locking either valve opening, said means consisting of a T-shaped lever comprising a leg and oppositely 20 extending arms, the leg being fulcrumed upon the cylinder intermediate its ends and the arms being disposed in operative proximity to the levers, and means carried by the lever and engageable with the cylinder 25 for locking said lever in its intermediate or either of its adjusted positions.

In testimony whereof, I affix my signature, in presence of two witnesses.

WADE H. EMRICK.
